UNITED STATES PATENT OFFICE.

ABEL SACK, OF ASHTON, NEBRASKA.

POWER-HAMMER.

SPECIFICATION forming part of Letters Patent No. 674,711, dated May 21, 1901.

Application filed November 27, 1900. Serial No. 37,878. (No model.)

To all whom it may concern:

Be it known that I, ABEL SACK, a citizen of the United States, and a resident of Ashton, in the county of Sherman and State of Nebraska, have invented a new and Improved Power-Hammer, of which the following is a full, clear, and exact description.

The object of the invention is to provide a new and improved power-hammer which is simple and durable in construction, very effective in operation, readily adjustable for different work, and completely under the control of the operator.

The invention consists of novel features and parts and combinations of the same, as will be fully described hereinafter and then pointed out in the claims.

A practical embodiment of the invention is represented in the accompanying drawings, forming a part of this specification, in which similar characters of reference indicate corresponding parts in all the views.

Figure 1 is a side elevation of the improvement. Fig. 2 is a rear end elevation of the same. Fig. 3 is a detail side view of the spring-pitman, and Figs. 4 and 5 are detail views of parts of said pitman.

On a suitably-constructed base A is held an anvil B, carrying a removable anvil-die C, over which operates a hammer-die C', removably held in a hammer D, having its handle D' in the form of a lever hung on centers E, carried by a link F, fulcrumed at its lower end at F' on the base A. A screw-rod G engages the link F and is pivotally connected at G' with a brace G², extending from the base A to the upright A', erected on the said base. A spring G¹ is coiled on the screw-rod G and presses on the link F, so as to hold the latter in position against a nut G³, screwing on the outer end of the screw-rod G. By adjusting the nut G³ the link F is caused to swing forward or backward, according to the direction in which the nut is turned, so as to shift the hammer D and its die C' relatively to the die C and in a transverse direction, according to the work in hand.

The top of the hammer D is pivotally connected by a yielding pitman H with the wrist-pin I' of crank-wheels I, secured on a shaft J, journaled in suitable bearings arranged on the standard A'. The crank-wheels I have

peripheral grooves engaged by belts K, connected with other machinery, so that a continuous rotary motion is given to said crank-wheels to impart a swinging motion to the hammer D by the pitman H. The latter is yielding in the direction of its length, and for this purpose consists of a head H', having bearings engaging the wrist-pin I', and from said head H' depends a tubular extension H², in which is fitted to slide the upper end of a shank H³, having its lower end pivotally connected with the top of the hammer D. On the shank H³ is secured a cross-head H⁴, through which extend guide-rod H⁵, secured to the head H'. On the guide-rod are coiled the springs H⁶ H⁷, pressing against the cross-head H⁴ on opposite sides, the springs H⁶ abutting at their lower ends against a connecting-piece H⁸, connecting the guide-rod H⁵ with each other. This piece H⁸ may be secured by the nuts, as shown in Figs. 1 and 3. By the construction described the pitman yields in the direction of its length, as an upward pressure of the hammer D on said pitman causes the cross-head H⁴ to press the springs H⁷, and on a downward pressure of the hammer H the cross-head H⁴ to press the springs H⁶. By hanging the hammer D on a link F, pressed outward by a spring G⁴, and by connecting the hammer D with a yielding pitman to the crank-wheels it is evident that the desired blow to be given can be struck with any desired pressure, and work of different kinds can readily be fashioned by this trip-hammer, owing to the yielding between the hammer and the crank-arm and the transverse adjustability of the hammer relatively to the anvil. The crank-wheels I are counterbalanced by counterbalancing-weights I² integral with said wheels and located diametrically opposite the wrist-pins I'.

In order to tighten or loosen the belts K to actuate and to stop the hammer D, I provide a suitable belt-tightener under the control of the operator and constructed as follows: Tightening-pulleys L are journaled on a bell-crank lever L' and are adapted to engage one run of the belts K, and the said bell-crank lever is fulcrumed on the upper end of the standard A' and is pivotally connected by a link L² with a lever N, likewise fulcrumed on said standard. A rod O pivotally connects

the outer end of the lever N, and this rod has its lower end mounted to slide in a suitable bearing O', attached to the standard at the back thereof. The rod O is formed with a cross-5 arm O², pivotally connected by links P with a treadle Q, fulcrumed on the base A and extending to the front of the machine, so as to be within convenient reach of the operator's foot. A spring O³ is coiled on the lower end 10 of the rod O and rests on the bearing O', and said spring serves to normally hold the rod O in an uppermost position to hold the tightening-pulleys L out of engagement with the belts K. (See Fig. 1.) When the belts K are not 15 tightened, they run loose around the crank-wheels I, and when it is desired to actuate the hammer D the operator presses the treadle Q, so as to impart a downward sliding movement to the rod O by the links P against the 20 tension of the spring O³. The downward movement of the rod O causes the swinging of the lever N and a similar movement of the bell-crank lever L' by the link L², so that the tightening-pulleys L are moved forward in 25 engagement with the belts K to tighten the same. When this takes place, the crank-wheels I are rotated to impart a desired swing- 30 motion to the hammer D.

When it is desired to stop the hammer D, 35 the operator releases the pressure on the treadle Q, so that the spring O³ returns the rod O and the parts connected therewith to their former positions. (Shown in Fig. 1.)

It will be noticed that the hammer-handle 35 is so supported that it can move longitudinally, so it can move outward by centrifugal action in making the stroke, and will be retracted by the spring G⁴, whereby there is secured a drawing stroke of the hammer.

Having thus fully described my invention, 40 I claim as new and desire to secure by Letters Patent—

1. A power-hammer having a pivoted handle or helve provided with the hammer-head, 45 an operating-crank, and a yielding pitman connecting the crank and hammer-head and arranged to swing at one end with the crank and at its other end with the head as the latter swings in its arc, substantially as set forth.

2. A power-hammer comprising the framing, the operating-crank, the hammer and the longitudinally-springing or resilient pitman between the crank and hammer, substantially as set forth.

3. A hammer apparatus substantially as described comprising the framing, the hammer-lever, an upright link pivoted at its lower end and pivotally connected at its upper end with the hammer-lever, a spring operating to force 55 said link in one direction in line with the direction of length of the hammer-lever, and screw devices for adjusting the said link in opposition to the said spring, substantially as set forth.

4. A hammer apparatus substantially as de- 65 scribed comprising the framing, the hammer and its handle or lever, means for operating the hammer, a support for said hammer, which support is movable in the direction of length of the hammer-handle and toward the ham- 70 mer-head, and a spring resisting such move- 75 ment of the support whereby the hammer as it is operated in making the stroke may move outward by centrifugal action and will be re- tracted by the spring, whereby there is se- cured a drawing stroke of the hammer, sub- stantially as set forth.

5. A power-hammer comprising the anvil, the hammer, operating means and a pitman yielding in the direction of its length, and comprising a head having a bearing for engagement with a wrist-pin and a tubular extension, a shank slidable in said extension and having means for connection with the hammer, guide-rods on said head, a cross-head 80 on said shank and engaging said guide-rods, and springs on said guide-rods and pressing the cross-head on opposite sides, as set forth.

6. A power-hammer having a hammer pro- 90 vided with a pivoted handle or lever, a drive- shaft having a pulley and a crank, a yielding pitman connecting the crank with the ham- mer, a drive-belt on the shaft-pulley, a tight- 95 ening-pulley arranged to bear against said belt, an angular lever carrying the tighten- 100 ing-pulley, a straight lever connected by a link with said angular lever, a spring-pressed rod connected with said straight lever, a treadle, and a link connecting the treadle with said rod, as set forth.

7. A power-hammer comprising the anvil, the hammer and its lever, the drive-shaft hav- 105 ing a crank, a longitudinally-yielding pitman between said crank and the hammer, a sup- port to which the hammer-lever is pivoted, 110 said support being movable in the direction of length of the hammer-lever, and a spring resis- 115 ting such movement of the support, sub- stantially as set forth.

8. A trip-hammer having an anvil, a ham- 110 mer, a lever carrying said hammer, a link on 115 which the hammer-lever is fulcrumed; a piv- 120 oted screw-rod engaging said link, and a spring pressing said link, as set forth.

9. A hammer apparatus comprising the 115 hammer-head, the crank, and the pitman se- cured at one end to the crank, and at its other end to the hammer-head, and springing lon- 120 gitudinally between its ends, substantially as set forth.

In testimony whereof I have signed my name to this specification in the presence of two subscribing witnesses.
